UNITED STATES PATENT OFFICE.

JOHN WAHL AND OTTO MELZER, OF BOROUGH OF QUEENS, NEW YORK, ASSIGNEES TO
A. SCHRADER'S SON, INC., OF BROOKLYN, NEW YORK, A CORPORATION OF NEW
YORK.

TUBE-DEFLATING MACHINE.

Application filed March 13, 1926. Serial No. 94,625.

This invention relates to improvements in tube deflating machines and has for its primary object the provision of mechanism which eliminates the use of spreading devices or other mechanical means for holding the opposite walls of the tube spaced apart at the foot of the tube valve, whereby to insure complete removal of the air from the tube after manufacture and inspection there-
10 of and preparatory to packing for market.

According to the present invention we provide a supporting device or saddle for the pneumatic tube of the general forms disclosed in the patents to Kraft, Nos. 1,297,-
15 186, 1,405,230 and 1,408,099, the latter two of which disclose means which depend, as does the preferred embodiment of this invention, upon the action of gravity to cause collapsing of the tube walls. However, instead of providing mechanical spreader means for holding the tube walls spaced apart at the foot of the valve casing, we provide an improved support and engaging means for the tube at the foot of the valve
25 casing. By virtue of said arrangement of parts, the walls of the tube at the foot of the valve casing are prevented from completely collapsing when the tube as a whole is collapsed by the gravity activated means and simultaneously with the collapsing of the tube, the tube valve thereof is unseated by a valve opening means. Preferably the interior of the tube at said time is placed through the valve casing thereof in communication with a suction means for withdrawing the air from the tube.

A preferred embodiment of our invention is illustrated in the accompanying drawings wherein,

40 Figure 1 is a transverse section of the device taken along the lines 1—1 of Fig. 2.

Fig. 2 is a side elevation of the device shown in Fig. 1.

Fig. 3 is a top plan view of the device shown in the preceding figures.

Referring to the drawings let A indicate a tube support or saddle which is in the form of a transversely arched sheet metal band over which the tube to be deflated is adapted to be mounted, said support being further adapted to co-operate with expanding means, which, upon being expanded against the inner periphery of the tube, cause the walls of the tube to collapse. The
55 tube is preferably so mounted that simul-

taneously with the collapsing thereof the valve casing B is received in a socket member C provided with a valve unseating means c, adapted to unseat the tube valve. The socket member C is connected by a tube 60 D or other conduit with a suction device adapted to withdraw the air from the tube. In Figs. 1 and 2 the tube D is shown as connected to a support E which is in communication with the suction device (not 65 shown). Usually a battery of ten or twelve deflating devices of the type herein disclosed are radially mounted about a central standard and in communication with a common suction pump, which arrangement permits a single workman to progressively handle a large number of tubes, since it will be understood that by the time a tube mounted on one support or saddle is wholly deflated, the workman will have been able to 70 mount for deflation a tube on each of the remaining supports of the battery. A tube deflating machine of this general type is described in detail in the Kraft Patent No. 1,297,186.

According to the present invention we completely do away with all mechanical means or spreader devices for holding the tube walls separated at the foot of the valve casing during the deflating operation. This 85 we accomplish by supporting or engaging the tube on its side wall at the point adjacent the valve casing, which is received within the socket member C, the tube being so supported that when the expanding means 90 are expanded against the inner periphery of the tube to collapse the walls thereof, the tube in collapsed condition will have its wall at a point adjacent the foot portion of the valve casing overlying and in spaced relation 95 to said foot portion. In Fig. 1 the tube in collapsed form is shown in dotted lines as assuming a substantially semi-circular or concave form, while the remaining portion of the tube assumes a flat collapsed condition 100 about the expanding means, as shown in Fig. 2. It will also be seen that the walls of the tube adjacent the foot portion of the valve casing are somewhat twisted, which also causes them to remain spaced apart. To 105 facilitate this action we mount a valve casing supporting member F upon the support or saddle A, said member F being formed with a longitudinal groove G, the base of which is inclined toward the center line or 110

median plane of the support or saddle. At the base or lower end of the inclined member the socket member C is secured in such position that its axis will coincide with the longitudinal axis of the valve casing B when supported upon the inclined surface of the member F. To further insure the proper positioning of the tube on the support or saddle we prefer to mount thereon at a point transversely opposite the member F an auxiliary tube supporting member H, the top face *h* of which is inclined in the same general direction as the inclined face on the member F, as will be best understood from an inspection of Fig. 1.

As herein shown, the member F is in the form of a casting bolted to the top of the support A, and the member H in the form of a sheet metal band bent into suitable form and also secured to the top of the member A transversely opposite and preferably in alignment with the member F. It will be understood, however, that both these elements may be formed integrally and either as a casting or entirely of sheet metal. It is also to be understood that the angularity of the inclined surface on the members F and H are merely illustrative of an arrangement of parts whereby the objects of the invention can be accomplished.

The expanding means for collapsing the walls of the tube may be of any preferred form, and as herein shown are the same as disclosed in the patent to Kraft, 1,408,099, dated February 28, 1922. Said means consists of the saddle A having straight legs *j*, *j'* arranged in reversed relation to A and mounted to slide up and down with respect to A. The member J is preferably guided in its upward and downward movements by a pair of tubular guides K, K' which are held at their upper ends with a cross-piece L. The member J is provided with rods *j*² and *j*³ which slide in the tubes K, K' respectively, the weight of the member J and its sides and rods *j*, *j'*, *j*², *j*³ is hence practically available to secure the proper tension on the tube. Means are provided for collapsing the expansible device, and as herein shown comprise a lever M pivoted to a plate N which is best formed as an integral part of a sector O. The lever M is connected to the member J by a rod P, which, when the lever is moved upwardly, elevates the member J to its fully collapsed position. The weight of the lever and connecting rod P also add to the effective weight of the member J. Means are also provided whereby the device may be forcibly expanded and held in expanded position. This may be accomplished by a downward pressure upon the lever M, and the device may be held in its expanded position by a pin Q which engages teeth R formed on the sector O. When the tube is fully deflated the lever may be

pushed slightly to the left to disengage the pin Q from the teeth R, the parts being sufficiently loose to permit this. Means are also provided for holding the member J in its upward or collapsed position during the operation of taking off the deflated tube and adjusting another in place. To this end there is provided a pin S which is mounted in fixed position and a pin T which is adapted to engage the pin S. This engagement may be made by shifting the lever to the right slightly, whereupon the two pins engage. They may be disengaged by a reverse movement.

In the operation of the device the tube is mounted over the auxiliary support H, the support or saddle A and the member J of the expanding means when in collapsed position with the valve casing B seating in the groove G of the inclined member F and with one side wall of the tube adjacent the valve casing B seating upon the inclined surface *h*. Upon operation of the expanding means the member J is permitted to drop by the action of gravity whereupon the tube as a whole is drawn downwardly, the valve casing B is also drawn downwardly over the incline of the member F, and the valve within the casing is unseated by the valve opener *c* within the socket C. Simultaneously with this operation the walls of the tube are collapsed, thereby forcing the air therefrom through the open valve and tube D and co-operating with the suction device to completely withdraw all the air from the tube. When the tube is completely deflated, the lever is elevated to collapse the device, the tube removed therefrom and packed for market.

While we have shown and described a preferred embodiment of our invention, we do not wish to be limited to the specific construction disclosed, since modifications thereof may be resorted to without departing from the spirit of the invention.

What we claim is:

1. A tube deflating mechanism comprising a support for a pneumatic tube, means for receiving a tube valve casing and unseating the valve therein, means for exhausting the air from the tube through the valve casing, and means for causing that part of the wall of the tube at a point adjacent the foot of the valve casing to overlie said foot in spaced relation thereto.

2. A tube deflating mechanism comprising a saddle upon which a pneumatic tube or the like can be mounted, and a socket member adapted to receive and open the tube valve when the tube is mounted on the saddle, the socket being offset to one side of the median plane of the saddle.

3. A tube deflating mechanism comprising a saddle upon which a pneumatic tube or the like can be mounted, and a socket member adapted to receive and open the tube valve

when the tube is mounted on the saddle, the axis of the socket being inclined to the median plane of the saddle.

4. A tube deflating mechanism comprising a saddle for a pneumatic tube or the like, means for supporting the valve casing of the tube in inclined position transversely of the saddle, and means for unseating the tube valve when the tube is mounted on the saddle.

5. A tube deflating mechanism comprising a support for a pneumatic tube or the like, a member having an inclined wall disposed transversely of said support, a socket member at the lower end of said inclined wall and a tube valve unseating device in said socket member.

6. A tube deflating mechanism comprising a support for a pneumatic tube or the like, means for supporting the valve casing in inclined position transversely of the support and for supporting the side wall of the tube adjacent the valve casing when the valve casing is placed in its supporting means, and means connecting with a suction device, adapted to receive the free end of the valve casing and unseat the valve therein.

7. A tube deflating mechanism comprising a member having an inclined transverse wall adapted to support a pneumatic tube or the like on its side wall, at a point adjacent its

valve casing, and a socket member laterally offset from the first member and extending transversely thereto for laterally receiving the valve casing of the tube and unseating the tube valve therein.

8. A tube deflating mechanism comprising means for supporting a pneumatic tube or the like on its side wall adjacent its valve casing, means adapted to be arranged within the supporting means and expanded against the inner periphery of the tube to collapse the tube, and a socket member offset to one side of the supporting means adapted to receive the valve casing and open the valve therein as the expanding means are expanded.

9. A tube deflating mechanism comprising means for supporting a pneumatic tube or the like on its side adjacent its valve casing, means adapted to be expanded against the inner periphery of the tube to collapse the walls thereof, whereby the tube in collapsed condition will have its walls adjacent the foot portion of the valve casing somewhat twisted, causing them to remain spaced apart, and means connecting with a suction device, adapted to receive the free end of the valve casing and unseat the valve therein.

In witness whereof, we have hereunto signed our names.

JOHN WAHL.
OTTO MELZER.
